(57) **CLAIM**

The ornamental design for the valve manifold, as shown and described.

DESCRIPTION

FIG. 1 is a front perspective view of a valve manifold according to the present disclosure;

FIG. 2 is a rear perspective view of the valve manifold of FIG. 1;

FIG. 3 is a front view of the valve manifold of FIG. 1;

FIG. 4 is a back view of the valve manifold of FIG. 1;

FIG. 5 is a top view of the valve manifold of FIG. 1;

FIG. 6 is a bottom view of the valve manifold of FIG. 1;

FIG. 7 is a right view of the valve manifold of FIG. 1; and,

FIG. 8 is a left view of the valve manifold of FIG. 1.

The broken lines in the drawings illustrating environmental structure or boundaries that form no part of the claimed design.

1 Claim, 6 Drawing Sheets
